PERCIVAL B. BERRY, OF BROOKLYN, NEW YORK, ASSIGNOR TO ENGLANDER SPRING BED COMPANY, OF BROOKLYN, NEW YORK, A CORPORATION OF NEW YORK.

SLIDING DOUBLE DAY BED.

Application filed February 26, 1924. Serial No. 695,171.

This invention relates to combined day beds and couches in which one section is shiftable relatively to the other to form either a double day bed, a single day bed or couch, and wherein operating means is provided for opening and closing the bed and preferably for opening and closing the foldable mattress thereof, an object of the invention being to provide improved means 10 for opening and closing the bed whereby a pair of ornamental heads may be used without interfering with such operating means.

A further object of the invention is the provision of a sliding day bed having improved means for opening and closing the bed so constructed and located as to permit the use of straight or unbent ornamental heads preferably of detachable form, and which operating means may also be utilized 20 to open and close a foldable mattress.

In the drawings accompanying and forming part of this specification, Fig. 1 is an end view of this improved sliding day bed, the dotted lines illustrating the sliding section 25 fully opened while the full lines illustrate it partially opened; Fig. 2 is a front view of the bed; Fig. 3 is an enlarged perspective end view thereof; Fig. 4 is a detail of the operating bar connecting bracket; and Fig. 5 is a detail of one portion of a head and the manner of detachably connecting it 30 with the end of the bed.

Similar characters of reference indicate corresponding parts in the several views.

Before explaining in detail the present improvement and mode of operation thereof, I desire to have it understood that the invention is not limited to the details of construction and arrangement of parts which 40 are illustrated in the accompanying drawings, since the invention is capable of other embodiments, and that the phraseology which I employ is for the purpose of description and not of limitation.

Heretofore in convertible couch or day beds, particularly sliding day beds constructed as for instance in accordance with patent to Luppino No. 898,981, dated September 15, 1908, which is owned by the 50 Englander Spring Bed Company, the assignee of the present invention, it has been found impossible to construct the couch with a head and foot due to the fact that the swinging means connected to the head sec-

tions and mattress for opening and closing 55 the same and extending beyond the ends of the bed could not operate or function with a straight or unbent head or foot juxtaposed to the end of the main section for it will be readily seen that if a head and 60 foot were connected to the main section, this would prevent the operation of the lever means for operating the shiftable section and mattress.

Thus, I have provided a very important 65 improvement in sliding beds of the kind described, which improvement has for a long time been unsuccessfully sought, it having been thought heretofore necessary to either bend the ornamental heads outwardly away 70 from the ends of the main section or to insert suitable heavy and cumbersome brackets so as to space the ornamental heads from the ends of the main section to provide 75 room for the operating bar and its connecting links, all of which however, I have done away with by the present improvement.

In the present embodiment this improved couch or day bed comprises a pair of relatively slidable sections 2 and 3, in the 80 present instance section 2 being the main section and stationary, and shiftable section 3, the top thereof comprising a spring fabric and the transverse cross or end bars shiftable beneath the top of the main section comprising the transverse or end bars 85 and spring fabric and therefore between the side bar and such spring fabric of the main section. Section 2 comprises a pair of end frames including transverse bars 4 having 90 a spring fabric 4^a permanently stretched therebetween, the cross bars 4 terminating in depending members 5. The members 5 are connected together by a suitable framework including the bars 6 and braces 7 connected to side bars 8, preferably formed of angle iron.

The depending members 5 are connected together by cross bars 9.

The sliding section 3 comprises end 100 frames including transverse cross members 10 connected together by a permanently stretched spring fabric 11. These transverse bars terminate in supporting legs 12. The end frames of the sliding section are 105 connected by suitable framework including side bars and suitable braces.

Secured to one of the sections, in the pres-

ent instance the main section, is an operating lever or bar 17 preferably U-shaped in form and of round or tubular formation so as to extend lengthwise over the top of the bed, the ends thereof being pivoted to angle formed brackets 18 (see Figs. 3 and 4), one secured to the top near the end of each transverse bar 4. The round form of the bar not only provides sufficient strength to 10 manipulate the sliding section and the heavy folding mattress and prevent any flexing or springing of the bar and therefore the wobbling of the parts, but it prevents the cutting of the fabrics of the stuffed 15 mattress when resting thereon and also of that part of the folding mattress which is attached or laced thereto. Thus the pivotal connection of the bar is in the preferred construction shown above the top or 20 spring of the main section. A link or bar 19 is pivoted at 20 to each end of the bar 17 and this link in turn is pivoted at its lower end as at 22 to a link 21, which extends inwardly and is suitably connected to 25 the sliding section. Thus it will be seen that by swinging the operating lever 17 in the direction of the arrow shown in Fig. 1 the sliding section will be shifted outwardly from its position underneath the main section 30 into an open position forming a double bed, the bar 17 being shifted completely over to rest upon the sliding section. The reverse movement of the bar will cause the sliding section to be shifted underneath the 35 main section, thereby closing the bed.

Connected to the main section 2 of the bed are a pair of ornamental heads 25, and by reason of the fact that the link 17 is connected to the angle brackets on top of 40 the cross member 4 and as the links 21 are flat pieces of metal, it is possible to bring the head members up close to the end frames of the main mattress section without interfering with the operation of these levers 45 and links. Hence, the lever operating bar 17 does not extend beyond the ends of the main section. The ornamental heads are shown detachably connected to the main section of the bed, this being accomplished 50 by providing each angle iron leg 5 of the main section with a pair of slots 30 formed in each leg and securing to each upright end post or member of the ornamental head a hooked bracket 31 having a pair of hooks 55 insertable into the slots 30. These hooks 31 extend upwardly and are located one above the other, and consequently the heads may be readily attached and detached.

The hook connections are located below 60 the operating parts of the bed. In the present instance suitable angle iron brackets 40 are located at each inner corner of the sliding section adapted to ride over the side bars of the main section and lift the inner 65 sides of the sliding section into a substan-

tially level position with the main mattress when the sliding section is extended. The sliding section is provided with casters and the main section with domes of silence and the weight of the main section may be carried by the ornamental heads if desired, although this is not strictly necessary. In other words, the main section may be supported by heads or the heads by the main section without departing from the present 75 improvement. In practice the foldable book mattress, not completely shown, may be connected with the operating bar 17 so as to open and close therewith.

Heretofore it has been found necessary, 80 in order to operate the sliding section of the couch bed of the form described to have the ends of the operating bar extend over the ends of the main section, and this prevented the use of ornamental heads of the straight 85 or unbent form, but by locating the ends of this operating bar on top of the main section and pivoting it by means of angle brackets within the ends of the main section and connecting it by flat links with 90 the sliding section, the use of ornamental heads of straight or unbent formation are not only permitted but these heads can be brought up close to the main section and connected therewith in the manner described, 95 since only sufficient space has to be provided for the operation of the flat links, and this is obtained by the use of the hooked brackets 31.

It is to be understood that by describing 100 in detail herein any particular form, structure, or arrangement it is not intended to limit the invention beyond the terms of the several claims or the requirements of the prior art.

Having thus explained the nature of my 105 said invention and described a way of constructing and using the same, although without attempting to set forth all of the forms in which it may be made, or all of the modes 110 of its use, I claim:

1. In a sliding day bed, the combination 115 of a main section, a sliding section, and means for opening and closing the sliding section and comprising an operating bar having a length less than the over-all length of the main section and pivotally connected to the top of the main section and link-connected to the sliding section, thereby to permit a pair of ornamental heads to be closely attached to the ends of the main section.

2. In a sliding day bed, the combination 125 of a main section, a sliding section, means for opening and closing the sliding section and comprising an operating bar having a 130 length less than the over-all length of the main section and pivotally connected to the top of the main section inside of the length thereby to permit the heads to be close coupled to the ends of said main section and

link-connected to the sliding section, and a pair of ornamental heads close connected to the ends of the main section.

3. In a sliding day bed, the combination of a main section, a sliding section, means for opening and closing the sliding section and comprising an operating bar connected to and inside of the length of one section and having a length less than the overall length of that section to which it is connected, thereby to permit the heads to be close coupled to the ends of said section, and link-connected to the other section, and a pair of ornamental heads close connected to the ends of the main section.

4. In a combined double day bed and couch, the combination of a main bed section, a shiftable bed section, a pair of ornamental heads connected to the ends of the main section in relatively close relation thereto, an operating bar shorter than the over-all length of the main section and pivotally connected to the top of the main section inside of the length thereof and link-connected to the sliding section, and means connecting the heads to the end section to form sufficient space for the linkage connection.

5. In a sliding bed, the combination of a main section including a stretched fabric and a side bar, a sliding section, the top thereof sliding between the side bar and fabric of the main section, means for opening and clos-

ing said sections and comprising a swinging operating bar connected to one of the sections at each end inside of the length thereof and linked to the other section, said operating bar having a length less than the overall length of the main section thereby to permit a pair of ornamental heads to be closely attached to the ends of the main section and a folding mattress having a part thereof connected to the operating bar and opened and closed by said operating bar on the shifting of said sliding section.

6. In a sliding bed, the combination of a main section including a stretched fabric and a side bar, a sliding section having the top thereof sliding between said side bar and fabric of the main section, means for opening and closing said sections and comprising a swinging operating bar connected to the main section at each end inside of the length thereof and linked to the sliding section, said operating bar having a length less than the overall length of the main section, a foldable mattress having a part thereof connected to the operating bar and opened and closed thereby on the shifting of the sliding section, and a pair of heads close-coupled to the ends of the main section.

Signed at Brooklyn, New York, this 23rd day of February 1924.
